UNITED STATES PATENT OFFICE.

CHARLES STOLLMERG, OF TOLEDO, OHIO, AND ERNEST R. PHILIP, OF ATLANTA, GEORGIA, ASSIGNEES TO AMERICAN CAN COMPANY, OF NEW YORK, N. Y., A CORPORATION OF NEW JERSEY.

SAP-RECEIVING APRON AND RECEPTACLE.

No. 857,847.

Specification of Letters Patent.

Patented June 25, 1907.

Application filed March 14, 1907. Serial No. 362,292.

To all whom it may concern:

Be it known that we, CHARLES STOLLMERG, a citizen of the United States, residing in Toledo, in the county of Lucas and State of Ohio, and ERNEST R. PHILIP, a citizen of the United States, residing in Atlanta, in the county of Fulton and State of Georgia, have invented a new and useful Improvement in Sap-Receiving Aprons and Receptacles, of which the following is a specification.

Our invention relates to improvements in sap receiving aprons and receptacles.

The object of our invention is to provide a sheet metal sap receptacle and an apron for supporting the same, and delivering the sap from the tree thereto, of a simple, efficient and durable construction, composed of few parts and capable of being cheaply manufactured, in which the weight of the sap receptacle and its contents will come directly upon the upright divergent end flanges of the apron which stiffen and strengthen the apron and adapt it to properly bear the weight of the receptacle and contents, and in which the receptacle can be conveniently removed from the apron for emptying it, while at the same time the receptacle will not be liable to be accidentally dislodged from the apron by animals or by wind.

Our invention consists in the means we employ to practically accomplish this object or result as herein shown and described.

In the accompanying drawing forming a part of this specification, Figure 1 is a front elevation of a sap receptacle and apron embodying our invention. Fig. 2 is a central vertical section. Fig. 3 is a central longitudinal section of the receptacle. Fig. 4 is an end view of the receptacle. Fig. 5 is a detail plan view showing the sheet metal blank in the flat from which the receptacle is formed and the lines upon which it is bent or folded in forming it.

In the accompanying drawing, A represents a portion of a turpentine bearing or other sap bearing tree in the cut *a* of which our improved sheet metal apron B is inserted, and D is our improved sheet metal sap receptacle coöperating with the apron and supported therefrom.

The sheet metal apron B is provided with an upper concavely curved edge *b* to facilitate its insertion in the cut *a* of the tree. At

its ends the apron B is provided with divergent upwardly projecting end flanges *b*¹, 55 each of which is provided at its upper part near the lower end of the apron with a downwardly extending inclined slot or notch *b*² to receive a wire or other hanger C on the sap receptacle D.

The one piece sheet metal sap receptacle D is preferably of a long, narrow, deep form, and consists of an integral bottom *d*, upright sides *d*¹ *d*² and flaring ends *d*³ and angle folds *d*⁴ *d*⁵, two of the angle folds *d*⁵ *d*⁶ having integral locking lips *d*⁶ at their outer edges which are folded inwardly over the upper edges of the flaring ends *d*³ to clamp the integral angle folds to the integral flaring ends of the vessel.

The upright longitudinal side *d*¹ of the vessel is preferably substantially at right angles to the bottom, but the outer upright side *d*² is preferably somewhat outwardly flared as indicated in the drawing. By having the inner longitudinal side *d*⁴ substantially at right angles to the bottom, the receptacle when supported from the apron B will keep a more upright position and be prevented from unduly tilting.

The receptacle D is provided at its upper edge and preferably at its inner upright longitudinal side *d*¹ with supporting hangers C. These supporting hangers C are preferably of wire, the two hangers being preferably formed in one piece and the body portion C' of the wire being embraced by the outwardly curled upper edge *d*⁷ of the upright side *d*¹ of the receptacle D.

The lower longitudinal edge or mouth *b*⁴ 90 of the apron B preferably fits between and is guided and embraced by the two opposing supporting hangers C C' of the receptacle D so that the hangers will prevent the receptacle from being dislodged from the apron 95 by a longitudinal movement. The lower edge or mouth of the apron projects over the upper edge of the inner side of the receptacle and under the inwardly turned hangers C C' so that the receptacle will not be accidentally dislodged from the apron by any up and down movement. The width of the hangers C or space between the same and the upper curved edge *d*⁷ of the receptacle slightly exceeds in extent the width of the upturned flanges *b*¹ on the apron B, so that by slightly

raising the receptacle it can be conveniently removed from the apron. While we have shown the supporting hangers C as made of wire and secured to the upper edge of the inner side of the receptacle, it will be understood by those skilled in the art that in our invention these supporting hangers may be variously constructed and variously applied to the receptacle.

10. We claim:—

1. In a sheet metal sap receiving receptacle and apron, the combination with a removable sap receiving receptacle furnished with supporting hangers, of an apron having at its outer end upwardly projecting divergent integral flanges provided with open slots therein for receiving the hangers, the lower portion of apron projecting between and under the hangers substantially as specified.
15. 2. In a sheet metal sap receiving receptacle and apron, the combination with a sap receiving receptacle having wire supporting hangers secured to its inner side at the upper edge thereof, of an apron having upwardly projecting divergent integral flanges at its outer ends provided with integral hooks for receiving the hangers on the receptacle, substantially as specified.
20. 3. The combination of a long, narrow, deep one piece sheet metal sap receptacle, provided with oppositely turned hangers on its inner side, of an apron having at its outer ends upwardly projecting flanges fitting between said hangers and furnished with slots to engage the same, substantially as specified.
25. 4. The combination with a sheet metal sap receptacle having integral bottom, sides, ends and angle folds and furnished at the upper edge of its inner side with an outwardly curved flange embracing the wire hanger of a wire hanger embraced at its body portion by said flange and having oppositely turned or facing hanger arms and an apron having at its outer ends upturned divergent flanges furnished with hooks fitting between and engaging the hanger arms, substantially as specified.

5. A one piece sheet metal sap receptacle having integral bottom, sides, ends and angle folds and locking lips folded over the angle folds, one of the upright longitudinal sides being substantially at right angles to the bottom, and the other flaring, substantially as specified. 55

6. A one piece sheet metal sap receptacle having integral bottom, sides, ends and angle folds and locking lips folded over the angle folds, one of the upright longitudinal sides being substantially at right angles to the bottom, and the other flaring, said receptacle being provided with hangers for supporting it, substantially as specified. 60

7. The combination with a sap collecting apron having divergent upturned end flanges provided with notches, of a removable sap receptacle having hangers fitting in the notches of the apron flanges, substantially as specified. 65

8. The combination with a sap collecting apron having divergent upturned end flanges provided with notches, of a removable sap receptacle having hangers fitting in the notches of the apron flanges, the lower portion or mouth of the apron projecting between and under the hangers, substantially as specified. 75

9. The combination with a sap collecting apron having divergent upturned flanges provided with notches, of a removable sap receptacle having hangers fitting in the notches of the apron flanges, the lower portion or mouth of the apron projecting between and under the hangers and over the upper edge of the receptacle, substantially as specified. 80
